COMBINED SNOWMOBILE SUSPENSION STAND
AND SAFETY GUARD OR SIMILAR ARTICLE

Charles F. Brightly, 3330 S. Cicero Ave.,
Cicero, Ill. 60650

Filed Apr. 5, 1971, Ser. No. 131,575

Term of patent 14 years

Int. Cl. D12—14

U.S. Cl. D41—1 D

FIG. 1 is a top plan view of the combined snowmobile suspension stand and safety guard embodying my new design.

FIG. 2 is a front elevational view thereof.

FIG. 3 is a side elevational view illustrating the combined snowmobile suspension stand and safety guard rotated 90° from the view shown in FIG. 2.

FIG. 4 is a rear elevational view illustrating the combined snowmobile suspension stand and safety guard rotated 180° from the view shown in FIG. 2.

I claim:

The ornamental design for a combined snowmobile suspension stand and safety guard or similar article, as shown.
